UNITED STATES PATENT OFFICE.

WILLIAM A. WHITFIELD, OF ASHEVILLE, NORTH CAROLINA.

CONCRETE-BLOCK MACHINE.

Application filed November 22, 1921. Serial No. 517,080.

To all whom it may concern:

Be it known that I, WILLIAM A. WHITFIELD, a citizen of the United States, and resident of Asheville, in the county of Buncombe and State of North Carolina, have invented certain new and useful Improvements in Concrete-Block Machines, of which the following is a specification.

This invention relates to machines especially adapted for use in manufacturing cement blocks.

An important object of this invention is to provide a cement block manufacturing machine having novel means whereby the sides and ends of the mold blocks are swung into position by the operation of a single lever so that the manufacture of the blocks is greatly expedited.

Further, by the use of the improved cement block forming machine the use of cores is dispensed with and the possibility of breaking the blocks due to the withdrawal of the core is consequently eliminated.

Further the use of crushed stone and a sufficient quantity of water is permitted thereby forming a block possessed of more than the usual strength.

A further object is to provide a cement block forming machine which is simple to operate, durable in use and cheap to manufacture.

In the accompanying drawings forming a part of this application and in which like numerals are employed to designate like parts throughout the same,

Figure 1 is a plan view of the improved block forming machine.

Figure 2 is a side elevation of the same.

Figure 3 is a side elevation of the machine, the view being taken at right angles to Figure 2.

Figure 4 is a perspective of a pallet embodied in the invention.

Figure 5 is a perspective of a spacing plate and associated elements embodied in the invention.

Figure 6 is a plan view of the member illustrated in Figure 4.

Figure 7 is a fragmentary perspective view of one of the end walls of the mold blocks.

Figure 8 is a detail elevation of one of the end walls of the machine.

Figure 9 is a fragmentary perspective of

a wall constructed from blocks made by the improved machine.

Figure 10 is a horizontal sectional view through one of the blocks.

In the drawing wherein for the purpose of illustration is shown the preferred embodiment of the invention the numeral 5 designates a frame which consists of a plurality of studs or corner beams 6 extended upwardly from a base 7 of rectangular or other suitable formation. As illustrated in Figure 2 the base 7 is formed from a plurality of stout beams, preferably two by six arranged on edge and having their ends connected in any suitable manner. The upstanding corner beams 6 may be bolted or otherwise secured to the inner sides of the base preferably at the corners of the same.

The corner posts 6 are formed at their upper ends with cross beams 9 which constitute a platform for supporting a pallet generally designated by the numeral 10 and illustrated in Figure 3. With reference to Figure 4 it will be obvious that the pallet consists of a pair of spaced sections arranged in spaced parallel relation to provide a longitudinally extending slot 11 for a purpose to be hereinafter described. End pieces 12 of any suitable material are arranged with the ends of the sections of the pallet by any suitable means.

The machine is provided with a pair of side members 20 having upstanding posts or beams 21 hingedly connected to the base as indicated at 22 and adapted to swing about a horizontal axis. A pair of opposed side walls 24 are secured to the upper portions of the posts 21 and overly the pallet 10 for the purpose of forming the opposite side wall of the mold box.

The end walls of the mold box are designated by the numeral 26 and are supported at the upper ends of the posts 27 hinged to the base 7 as indicated at 28. With reference to Figure 1 it will be observed that the end walls 26 are arranged between the side walls 24 and also overly the pallet 10 so as to complete the mold box. The intermediate portions of the side walls 24 are provided with recesses 30 which receive a quantity of cement for providing the centrally arranged lug or rib 31 at the intermediate portion of the block 32. The end portions of the side walls 24 may also be provided with cut

away portions 34 which receive a quantity of cement for providing the lugs 35 at the ends of the several blocks formed at each operation of the machine.

5 The mold box formed by the side and end walls and pallet is divided into a pair of compartments by means of a center plate generally designated by the numeral 38 and clearly illustrated in Figure 5. The center plate 38 consists of a plurality of sides 39 maintained in spaced relation by means of spacing strips 40, the lower portions of the intermediate spacing strips 40 being connected in any suitable manner to a vertically movable shaft 42.

10 The vertically movable shaft 42 which is rigidly connected to the center plate 38 is slidably through a guide beam 43 secured to the base 7. The center plate 38 is slidable through the longitudinal slot 11 in the pallet plate so that the pallet plate constitutes a guide for the center plate.

15 Upon the completion of the block or blocks the center plate 38 is moved downwardly by a lever 50 pivoted intermediate its ends to the vertically movable shaft 42 as indicated at 51 and pivoted at its forward end to a bracket 53 carried by one of the corner posts 6 of the same. The lever 50 extends diagonally of the machine and is provided with a handle 54 adapted to be depressed by the operator when it is desired to lower the center plate. On the other hand when it is desired to elevate the center plate 20 preparatory to the manufacture of a pair of blocks the lever 50 is elevated for moving the center plate up between the side walls 24 and the end walls 26.

25 The end walls are moved inwardly simultaneously with the upward movement of the center plate by means of a pair of links 60 pivoted to the intermediate portion of the end members by means of brackets 61 and pivoted to the upper portion of the vertically movable shaft 42 by means of collars 64.

30 A yieldable driving connection is established between the shaft 42 and the collar 64 by means of a coiled spring 65 mounted upon the shaft between the collar 64 and the collar 66 which as illustrated in Figure 1 is secured on the shaft by a set screw 67.

35 The end walls are movable inwardly in the path of the side walls, the latter being connected to the vertically movable shaft by means of links similar to the links 60 and which are connected to a collar 68 secured on the shaft above the collar 64 and held thereon by means of a set screw 69 or other suitable fastening means. By an adjustment of the screw 69 the collar 68 may be secured in any desired position to regulate the movement of the side walls 24 with relation to the end walls.

40 In operation the end walls are moved inwardly simultaneously with the upward

movement of the center plate and the side walls move inwardly after the end walls. When the end walls reach the limit of their inward movement the spring 65 retracts and the vertical movement of the shaft 42 continues for completing the inward movement of the side walls. Retaining strips 78 are arranged at the ends of the side walls 24 and overly the end walls 26 so as to firmly hold the end walls against outward movement when the material is packed in the several compartments. The end walls are limited in their outward movement by means of U-bolts 79 forming guides slidably receiving the upstanding posts of the end walls. 80 The terminal portion of the bolts are of course screw-threaded and are extended through a stationary portion of the frame and are engaged by suitable nuts.

85 The center plate 38 is provided with stripper bars 82 which are arranged in spaced parallel relation to the center plate and move upwardly flatly in engagement with the inner walls of the recesses 80 in the side walls 24. When the downward movement of the center plate 38 begins the stripper bars 82 also move downwardly so as to prevent the block formed from being mutilated.

90 As illustrated in Figure 5 the stripper bars 82 are secured to the lower longitudinal edge portion of the center plate 38 by means of diverging branches 85.

95 The center plate has its sides 39 arranged in spaced relation to form slots at the ends of the center plate, which slot receives the inwardly directed rib of the guide plate or strip 87 secured to the inner side of the end walls 26. As illustrated in Figure 2, additional guide strips 88 are secured to the inner sides of the upper beam 9 and slidably form 100 a means for directing the center plate in its vertical movement. Of course, the guide strips 87 are aligned with the guide strips 88 so that the center plate will not be interrupted in its vertical movement. In fact the 105 center plate is at all times engaged with the lower pair of guide strips 88.

110 One of the side members 24 is provided with latch bars 90 hinged adjacent their forward ends as indicated at 91 to the upper 115 portion of the side member and having their rear portions provided with lifting handles 92. When the side member 20 is swung outwardly the latch bars 90 are inclined as illustrated in Figure 3 and when the side members are swung inwardly the jar incident to this movement swings the several latch bars inwardly so that the locking devices 93 carried thereby are engaged with the opposite side member. By this means the oppositely 120 arranged side members are securely held in position.

125 Having thus described the invention what I claim is:—

1. A machine for manufacturing concrete 130

- blocks comprising a frame having a platform, a pallet mounted on said platform and having a slot, a center plate movable through said slot and having a vertically movable 5 shaft, an operating lever connected intermediate its ends to said shaft and at its forward end to said frame, side and end walls having posts hinged at their lower ends to said frame, collars arranged on said shaft, 10 links establishing connection between said posts and said collars, means carried by said side walls for holding said end walls against outward movement, a coiled spring mounted 30 on said shaft and providing a yieldable connection between said shaft and the end walls, and stationary guide members engaged with said center plate and connected to said platform. 35
2. A machine for manufacturing concrete blocks comprising a frame having a platform, a pallet mounted on said platform and having a slot, a center plate movable through said slot and having a vertically movable shaft, an operating lever connected intermediate its ends to said shaft and at its forward end to said frame, side and end walls 15 having posts hinged at their lower ends to said frame, collars arranged on said shaft, 20 links establishing connection between said posts and said collars, means carried by said side walls for holding said end walls against outward movement, and a coiled spring mounted 40 on said shaft and providing a yieldable connection between said shaft and the end walls. 25
3. A concrete block machine comprising a platform, a center plate movable through said platform and having a vertically movable shaft, an operating lever connected intermediate its ends to said shaft and mounted 45 at its forward end for pivotal movement, a frame supporting said platform and having pivotal connection with said lever, side and end walls having posts hinged at their lower ends to said frame, collars arranged 45 on said shaft, links establishing connection between said posts and said collars, and means mounted on said shaft for providing a yieldable connection between said shaft and the end walls.

WILLIAM A. WHITFIELD.
